UNITED STATES PATENT OFFICE.

WILLIAM LEE PILKINGTON, OF ST. HELENS, ENGLAND, ASSIGNOR TO HIMSELF,
WILLIAM PILKINGTON, THOMAS PILKINGTON, WILLIAM W. PILKINGTON,
RICHARD PILKINGTON, AND GEORGE H. PILKINGTON, OF SAME PLACE.

DESIGN FOR THE SURFACE ORNAMENTATION OF GLASS.

SPECIFICATION forming part of Design No. 22,099, dated January 3, 1893.

Application filed November 19, 1892. Serial No. 452,582. Term of patent 14 years. Patented in England August 12, 1892, No. 196,748.

To all whom it may concern:

Be it known that I, WILLIAM LEE PILKINGTON, of St. Helens, Lancashire, England, have invented a new and original Design for the Surface Ornamentation of Glass, (for which I have obtained Letters Patent in England, No. 196,748, dated August 12, 1892,) of which the following is a full, clear, and exact description.

Reference is to be had to the accompanying drawings forming a part of this specification, in which Figure 1 is a face view of a piece of glass embodying my new design and Fig. 2 is a sectional view of the same.

The design consists in the configuration shown. Thus *a* indicates rosettes, which appear in parallel rows, those of adjacent rows being out of line, a transverse line drawn through the center of one passing between two rosettes of the next adjacent row. The

rosettes are in the form of whirls, consisting of the arms *b* that emanate from a common center *c* and curve in the same direction, the curve being pronounced at the outer ends, said outer ends being enlarged. The rosettes form scalloped circular borders *d*, and the several borders form triangular figures *e*, said figures, between each two rows of rosettes, appearing in longitudinal series in serpentine order.

30
I claim:

The design for the surface ornamentation of glass, herein shown and described.

WM. LEE PILKINGTON.
